CLAIM

The ornamental design for a tail light as shown and described.

DESCRIPTION

FIG. 1 is a front, top, and right perspective view of a tail light showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, bottom, and left perspective view thereof; and,

FIG. 9 is an enlarged view of portion 9 shown in FIG. 1. The broken lines shown in the drawings represent portions of the tail light that form no part of the claimed design. The Long-Short broken lines encircling an enlargement portion of the design forms no part of the claimed design.
